UNITED STATES PATENT OFFICE.

ALANSON P. BRUSH, OF DETROIT, MICHIGAN.

CHASSIS-FRAME FOR MOTOR-VEHICLES.

1,120,900.

Specification of Letters Patent. Patented Dec. 15, 1914.

Application filed October 21, 1913. Serial No. 786,404.

To all whom it may concern:

Be it known that I, ALANSON P. BRUSH, a citizen of the United States of America, residing at Detroit, in the county of Wayne 5 and State of Michigan, have invented certain new and useful Improvements in Chassis-Frames for Motor-Vehicles, of which the following is a specification, reference being had therein to the accompanying drawings.

The invention relates to motor vehicle frame construction, and it is the primary object of the invention to increase the strength as well as to reduce the weight, by utilizing 15 members which have heretofore been auxiliary or mere attachments to the frame, as structural portions thereof.

It is a further object to so combine these elements that each, in addition to the performance of its usual function, will coöperate with the other elements to strengthen the structure as a whole.

Still a further object is to obtain a construction in which the elements usually employed are dispensed with and the functions thereof performed by other elements primarily designed for distinct functions.

With these objects in view, the invention comprises various features of construction 30 as hereinafter set forth.

In the drawings: Figure 1 is a plan view of the frame; Fig. 2 is a side elevation thereof; Fig. 3 is a perspective view of a number of the elements composing the 35 frame detached, but in position for assembly; Fig. 4 is a similar view of the assembled elements; and Fig. 5 is a cross section.

In the present state of the art of motor 40 vehicle construction, there are certain elements which are universally used, such, for instance, as the side sills of the frame, the running-board, cross connections between the side sills, etc. Some of these elements, 45 such as the side sills and running-board, are functionally distinct and, although attached to each other, do not otherwise coöperate. These sills are not strengthened by the attachment of the running-board thereto, but 50 only form a support for the latter; and, on the other hand, the running-board is entirely independent in function from the sills. With my improved construction these two 55 elements are so combined that the sill is an essential part of the running-board and the running-board an essential part of the sill,

while the combined structure is stronger in proportion to its weight than with constructions heretofore used.

In detail, A is the side sill of the chassis frame, and B are the running-boards. It is usual to form side sills of channel cross-section, the upper and lower flanges forming respectively compression and tension members of a truss or structural beam. With my construction the lower flange may be entirely dispensed with in that portion of the sill which is adjacent to the running-board, and the running-board is so designed as to perform the function of this flange when attached. More in detail, the central portions of the sills A are formed with an upper inwardly-extending flange C and a downwardly-extending web D, thereby forming an inverted L or angle bar. The running-board is formed of a laterally-extending sheet E of the desired width, having downturned strengthening flanges F and F' at its opposite sides, the former being riveted or otherwise rigidly attached to the lower portion of the web D, and the latter being preferably tapered from center to ends to form a truss. This produces of the combined structures a Z-bar section, which has the essential properties 85 of a truss. Furthermore, the web portion D forms the side shields or closure for the space between the running-board and the body, as well as a means for attaching and supporting the latter, so that several 90 parts usually employed in running-board construction are dispensed with—such as separate shields and separate supporting brackets.

To further increase the strength, the ends 95 of the running-board are bent upward, preferably in a curve, thereby forming brackets or braces G between the horizontal portion and the vertical web. They further form a convenient means of attachment to the 100 wheel fenders and a supporting brace therefor.

As the running-board extends only a portion of the length of the side sills, it is preferable to provide other means for forming 105 the lower flange in the portions extending beyond said support. I therefore provide said extension portions H and I with lower flanges J, which may be formed integral with the web D, and to avoid any point of 110 weakness these flanges overlap the portion attached to the running-board and are ta-

pered, as shown at K. If desired, the extensions may be formed of separate members from the central portion of the sills, such a construction being shown in the 5 member I. This member, as more clearly shown in Fig. 3, has its outer portion L of a channel cross section, and which is arranged above the plane of the central portion of the sill. At its inner end the member I merges into a downwardly-extending web M, which is fashioned to fit around the curved end G of the running-board and to be attached to the depending flange F thereof.

15 As generally constructed the chassis has an open frame, and the body of the vehicle which is mounted on this frame is provided with a floor. With my construction the floor may be formed as a portion of the 20 frame, which will increase the strength and rigidity of the latter, particularly in operating as a substitute for a gusset between the side sills and cross bars, and also as an extension of the upper or compression 25 flange of the side sills, increasing the strength thereof. Thus, as shown in Fig. 5, the floor N is formed of a metallic plate, which is riveted or otherwise secured to the upper flanges C of the sills and extends substantially in the plane thereof from one side to the other. This plate further forms a longitudinal brace for the frame where the side sills are curved, to decrease the width 30 at the front end.

35 The cross bars of the chassis frame are usually arranged in the plane of the side sills or below the same and have no functional relation with the body of the vehicle. On the other hand, in the construction 40 of vehicle bodies the space between the seat and the floor is usually inclosed by a vertically-extending board. I have structurally combined these two elements by forming a cross-brace O of a metallic bar, 45 so positioned as to extend beneath the seat and to close the space between the same and the floor. This bar, as shown in Figs. 3, 4 and 5, has an upper flange P, which is secured to the upper flange L' of the sill 50 extension L, and a lower flange Q which is attached to the upper flange C of the sill A and also to the floor plate N.

55 From the above description it will be understood that my improved structure is an organized unit, in which the structural elements are combined in a novel manner, contributing both to increased strength and diminished weight.

60 What I claim as my invention is:

65 1. In a motor vehicle frame adapted to support a body separable therefrom, a side sill separate from the body and a running board combined as a unit, said running board forming a strengthening flange for said sill, and the web portion of said sill,

forming a closure between the running board and the body.

2. In a motor vehicle frame adapted to support a body separable therefrom, a side sill and a running board combined as a unit, 70 said running board forming a strengthening flange for said sill, and the web portion of said sill forming a closure between the running board and body, and a depending flange at the outer edge of the running 75 board for strengthening the same.

3. In a motor vehicle frame adapted to support a body separable therefrom, a side sill and a running board combined as a unit, 80 said running board forming a strengthening flange for said sill, and the web portion of said sill forming a closure between the running board and body, and an angle brace between said running board and web.

4. In a motor vehicle frame adapted to 85 support a body separable therefrom, a side sill and a running board combined as a unit, said running board forming a strengthening flange for said sill, and the web portion of said sill forming a closure between the running board and body, a depending flange at 90 the outer edge of said board, and an angle brace between said running board and the web portion of said sill.

5. In a motor vehicle frame, a sill having 95 a web portion and a single flange extending laterally therefrom, a running-board secured to said web portion to form a second flange therefor, and a double-flanged section of said sill beyond said running board. 100

6. In a motor vehicle frame, a side sill having a central portion of L cross section with a vertically-extending web portion, a running board secured to said portion and extending laterally therefrom, the end of 105 said running-board being upturned and secured to said web to form a brace, and a double-flanged portion of said sill extending beyond said running-board.

7. In a motor vehicle frame, a side sill 110 having single and double flange portions in different lengths thereof, and a running-board secured to said single flange portion and constituting a second flange therefor.

8. In a motor vehicle frame, a sill having 115 a laterally-extending flange at one edge of its web portion and a second laterally-extending flange at the opposite edge of said web portion for a portion only of the length thereof, said flange having a tapering inner 120 end portion, and a running-board secured to said web forming a complementary flange and overlapping the tapered portion of the shorter flange.

9. In a motor vehicle, a side sill having a 125 vertical web portion, and a floor plate constituting an upper laterally-extending flange for said web, and a running-board constituting a lower laterally-extending flange for said web. 130

10. In a motor vehicle frame, a floor plate and a running-board in different horizontal planes, and a sill having a vertical web uniting said floor plate and running-board and rigidly secured thereto to form there-with a truss. 30
11. In a motor vehicle frame, a side sill having a vertical web portion, a running-board secured to the lower edge of said web portion, and an upturned end for said running-board forming a brace connection to said web and a means of attachment for the wheel fender. 35
12. In a motor vehicle frame, the combination with the side sills, of a floor extending between said sills, and a cross bar also extending between said sills arranged between said floor and the vehicle seat and forming a closure for the space therebetween. 40
13. In a motor vehicle frame, a sill having a vertical web portion, a laterally-extending flange forming a running-board, and an angle brace between the running-board and the web. 45
14. In a motor vehicle frame, a sill having a vertical web portion, a laterally-extending flange forming a running-board, and a depending flange at the outer end of said running-board increasing in depth from ends to center. 50
15. In a motor vehicle frame, a sill having a vertical web portion, a laterally-extending flange forming a running-board, angle braces at the ends of said running-board connecting the same with said web, and a depending flange at the outer edge of said laterally-extending flange, increasing in depth from the ends toward the center of said running-board to form a truss. 55
16. In a motor vehicle frame, a sill having a vertical web portion, a laterally-extending flange forming a running board, and a depending flange at the inner edge of said running board attached to said vertical web portion. 60
17. In a motor vehicle frame, a sill having a vertical web portion, a laterally-extending flange forming a running board, and down-turned strengthening flanges at opposite sides of said running board. 65

In testimony whereof I affix my signature in presence of two witnesses.
